Primary Examiner — Elizabeth J Oswecki(74) *Attorney, Agent, or Firm* — Squire Patton Boggs (US) LLP(57) **CLAIM**

The ornamental design for a shoe sole for flying disc sports, as shown and described.

DESCRIPTION

FIG. 1 is a right side, perspective view of a shoe sole for flying disc sports showing our new design;

FIG. 2 is a left side, perspective view thereof;

FIG. 3 is a right side view thereof;

FIG. 4 is a left side view thereof;

FIG. 5 is a front view thereof;

FIG. 6 is a back view thereof; and,

FIG. 7 is a bottom view thereof.

The broken lines shown in the drawings represent portions of the shoe sole for flying disc sports that form no part of the claimed design.
